TEN-KEY ADDING AND LISTING MACHINE

1,301,941.

Specification of Letters Patent. Patented Apr. 29, 1919.

Application filed May 29, 1916. Serial No. 100,530.

To all whom it may concern:

Be it known that I, OLIVER D. JOHANTGEN, a citizen of the United States, residing at Chicago, in the county of Cook and State 5 of Illinois, have invented a certain new and useful Improvement in Ten-Key Adding and Listing Machines, of which the following is a full, clear, concise, and exact description.

10 My invention relates to improvements in computing machines and more particularly to ten key adding and listing machines. The more important objects of the invention are; to provide a machine having a 15 single member differentially positioned by the actuation of any of the keys, such member serving both as a rack to engage and operate successively the gear wheels of the accumulator and as a type bar having type 20 mounted thereon which it strikes against the platen to print; to provide a machine wherein a reciprocable member is moved longitudinally by the keys to operate the accumulator and to position the type with respect 25 to the printing line and is thereafter moved transversely by the further actuation of the keys to disengage it from the accumulator and cause it to strike the type against the platen; to provide a machine of this character 30 having means for holding said reciprocable member out of engagement with either the accumulator or the platen during its return movement and to lock it at the conclusion of such movement to prevent rebounding or any other movement, except as 35 the keys are depressed; to provide means in such a machine for insuring uniform resistance of the keys when actuated; to provide a machine having an accumulator carriage 40 movable laterally with respect to the adding rack, in conjunction with a lever for initially positioning said carriage in accordance with the number of digits in the item to be registered; to provide means co-operating with said accumulator carriage to prevent the actuation of keys in excess of those 45 necessary to properly register the item; and to provide an adding and listing machine of greatly simplified construction and one 50 lending itself to economical manufacture. Other objects of the invention will be apparent without specific enumeration thereof.

In the accompanying drawings I have illustrated one embodiment of the invention.

55 It is to be understood however, that the in-

vention is susceptible of various other embodiments, the one shown being considered typical.

Figure 1 is a side elevation of the complete machine. 60

Fig. 2 is a top plan view of the body of the machine with the cover removed.

Fig. 3 is a rear elevation of the machine with the cover removed.

Fig. 4 is a section on the line 4-4 of 65 Fig. 2.

Fig. 5 is a similar section with some of the parts moved to a different position.

Fig. 6 is a side elevation of the full stroke mechanism. 70

Fig. 7 is a similar elevation showing the mechanism locked against operation.

Fig. 8 is a similar elevation of the mechanism in an intermediate position.

Fig. 9 is an elevation of a supporting plate. 75

Fig. 10 is a top plan view of an escape- 80 ment operating mechanism and sub-total mechanism.

Fig. 11 is an elevation thereof.

The machine selected to illustrate the various features of the invention is one having ten digit keys and a single combined accumulator rack and printing rack arranged to be differentially positioned by the actuation of any of said keys. The machine 85 is key actuated, all the keys having the same throw and being uniformly tensioned, despite the variable travel of the said rack. A carriage is provided, which contains the accumulator and a platen to the rear thereof. 90 The rack reciprocates vertically between the accumulator and platen. During the up-stroke of the rack it is in engagement with one of the accumulator wheels, but out of contact with the platen. At the end of the 95 up-stroke, the keys have not quite completed their down-stroke, the final movement of the latter serving to throw the rack to the rear, thereby disengaging it from the accumulator wheel and causing the type to strike 100 against the platen. During the upward or return movement of the key which has been depressed, the rack drops, its downward movement being insured by spring-actuated means which also locks it in lowermost position to prevent accidental upward movement. During such downward movement, it is held in intermediate position, out of contact with the accumulator and the platen. 105

In order to position the carriage, the op- 110

erator depresses a denominational order key on a pivoted lever and swings the latter to one side. Said key serves to limit the movement of the lever, and hence of the carriage, thereby positioning the accumulator so that the first digit entered in the register will be printed in the proper column, that is, the one representing the left hand digit of the item to be registered. In other words, in 10 the machine under consideration, the item is entered by reading the digits from left to right in their natural order, the carriage having an escapement which moves it back one step at a time to its initial position. 15 However, the carriage may be arranged to move in the reverse direction to accommodate operators who are accustomed to entering the item from right to left.

The carriage and associated parts are 20 made the subject of a separate application Serial Number 100,531, also filed May 29, 1916, and hence are not described in detail or claimed herein.

The frame of the machine consists essentially of side members 1, 2, of any suitable configuration, held in fixed spaced relation by transverse rods 3, 4, 5, 6. Said plates are also spaced by a vertical plate 8 in the front of the machine, having its ends flanged over 30 at 9 and suitably secured to the side plates, the rear ends of said plates being similarly spaced apart by a vertical plate 11. A transverse member 15, bent to form an angle iron, is also secured to said side plates. An additional transverse member 22 in the form of an angle iron is similarly secured to the side plates at opposite ends by additional brackets 23. A casting 24 is arranged across the front of the machine near the lower 35 part thereof, and has a pair of extensions 25 constituting feet which support the front of the machine. An additional pair of feet 26 are arranged at the rear corners consisting of small castings secured to the side and 40 rear plates.

The keys are all alike, except as to the configurations of their front ends, whereby they may be considered as of two forms, 30, 31. The key caps 32 are arranged in two 45 rows, one higher than the other. The keys are pivoted about the cross rod 3 and are spaced apart by collars 33. The front end of said keys project through slots 34 in the plate 8 and are guided thereby in their vertical movement. Locks having the form of pivoted arms 35 are provided to prevent depression of more than one key at a time. Said keys are normally held with their front ends in elevated position by means of springs 36 secured thereto and to the angle bar 22. Upward movement of said front ends is limited by the engagement of the rear ends of said keys with collars 37 on the cross rod 6. The keys all have the same throw, that is, they swing through the same angle, re-

gardless of the digit represented thereby. As the rear ends of said keys swing upwardly, they engage a transverse member and carry said member upwardly, each key having a different travel prior to engagement therewith. Said member has the form of a stepped plate 40 having a series of upper steps or notches 41 and a corresponding set of lower notches 42, whereby it has a differential movement, depending on which 75 key is depressed. The plate is secured at opposite ends to a pair of brackets 43 secured to a pair of similar arms 44, which arms are pivotally mounted on the cross rod 3 at their forward ends and are connected 80 at their rear ends by a cross bar 45 carrying a combined accumulator actuating rack and type rack 46 hereinafter described.

Instead of providing for direct engagement between the rear ends of the keys and 85 the lower series of notches 42 on the stepped plate 40, I provide a slightly yielding engagement for a purpose hereinafter described, by virtue of a spring 50 on each key fastened at its forward end to the bent over 90 portion of a lug 51 and sprung so that its rear end tends to spring upwardly, said rear end however, being restrained by a second bent over lug 52. The springs are stiff enough so that, as the front of any key is 95 depressed, said springs engage the various steps 42 and carry the plate 40 and the arms 44 upwardly. The upward movement of said plate is limited by a series of ten similar stop levers 55, each pivotally mounted on 100 the cross rod 6 and normally held in the position shown in Fig. 4, by the engagement of its inclined front surfaces 56 with the lug 52. Said stop locks are held in said position against the action of a series of 105 springs 57 secured thereto and to the vertical flange of the angle iron 15 which springs tend to rock said stop bars and project the stops 58 forwardly into the path of travel of the stepped plate 40. 110

It will be seen that as any key is rocked about its pivotal support, the corresponding stop lever 55 is permitted to swing forwardly as the locking lug 52 slides upwardly along the cam surface 56, whereby the corresponding stop 58 is projected into the path of travel of the stepped plate 40, thereby permitting one of the series of steps 41 to be positively engaged by said stop, limiting said upwardly movement. By this arrangement, it will be seen that a differential throw of said plate 40 is provided for. 115

A universal bar 60 is arranged in contact with the lower sides of all of the keys 30, 31, and is secured at opposite ends to a pair 120 of arms 62, 63, pivotally mounted about the cross bar 3. Said universal bar is normally impelled upwardly by a spring 64 secured to the arms 62 and the angle bar 22.

A lever 65 is also mounted on the cross 125

rod 3 near the center of said rod, its forward end projecting through an opening in the universal bar 60, whereby the two swing together. The rear end thereof carries a stud 66 and an eccentric stud 67, (see Fig. 4). Adjacent to the lever 65 is a plate or printing cam 68, also pivotally mounted on the cross rod 3. A spring 69 is arranged between said lever and plate with its ends hooked over opposite edges thereof, whereby said printing cam tends to swing forwardly with said lever when the rear end thereof moves forwardly, unless said printing cam is restrained by a locking mechanism, hereinafter described. Said printing cam tends to swing forwardly with respect to the lever 65, but is held against such movement by the stud 66 which is engaged by the rear of a slot 70 in said printing cam. The stud 67 is also arranged to travel in a slot 71 in said printing cam. Said studs serve to guide the movement of said printing cam, as well as performing other functions.

The printing cam has a cam surface 75 thereon which, during the forward swinging movement of said cam is adapted to engage a roller 76 mounted on a printing lever or bell crank lever 77, the latter being mounted on the cross rod 5. The upper arm of said printing lever is normally drawn forward by a spring 78 secured to said angle iron 22. Said forward movement however, is obstructed by a member constituting part of the carriage, and not shown herein. The function of said cam and lever is to throw the type rack bar 46 rearwardly through a small angle to cause the dis-engagement of said rack bar from the accumulator wheels and to cause the type to strike against the platen.

The printing cam 68 is normally held against forward movement by an arm 80 pivoted about the cross rod 5 and having a lateral projection 81 thereon engaged by a shoulder 82 on said printing cam. Said arm also has a downwardly projecting extension 83 at its forward end the lower surface of which constitutes a cam 84 and is adapted to be engaged by the eccentric portion of the stud 67 when the latter approaches the end of its travel in the slot 71 in said printing cam. Said engagement rocks the arm 80 thereby releasing said printing cam and allowing it to swing forwardly under the impulse of the spring 69, which has had its tension increased due to the forward movement of the lever 65. As said cam plate swings forwardly, the cam surface 75 thereon engages the roller 76, thereby rocking the printing lever 77 and abruptly moving the type bar rack 46 rearwardly, as previously stated. Engagement between said type bar rack and printing lever is effected by means of a stud 85 which slides in a slot 83 in said rack. The proper timing of the operations

just described may be effected by the adjustment of the eccentric stud 67.

During the upward movement of said rack bar, it is in engagement with the accumulator wheels, as hereinafter described, but during its downward movement, after striking the platen, it is desirable to hold it in intermediate position out of engagement with either said accumulator wheels or said platen. To accomplish this purpose, means are provided for holding said printing lever 77 in what is almost its rear position. Said means comprises a latch 87 carried by said bell crank lever on a stud 88 and normally impelled upwardly by a spring 89. A shoulder 90 on said latch engages a bent-over lug 91 on a fixed plate 92, (Fig. 4), when the rack bar 46 is in any position except its lowermost position. In said figure, said rack bar is in lowermost position, showing the pin 93 thereon as having engaged the latch 87 and moved it out of engagement with said shoulder 91, permitting said rack bar to be drawn to its normal forward position by its printing lever 77 and spring 78.

It will be seen that the upward movement of the type bar 46 is stopped before said bar is thrown rearwardly to print, by virtue of the fact that the lug 81 is not withdrawn from locking engagement with the shoulder 82 on the printing cam 68 until after the stepped plate 40 is moved to the extreme limit of its upward position carrying the printing rack 46 to its upward limit. An additional further movement of the key levers 100 is permitted however, by reason of the springs 50, as previously described, whereby the cam plate causes the operation of the printing lever 77 after the printing rack 46 has come to rest. This prevents the accumulator wheels from overthrowing. The pawl 95 and ratchet 96 prevent dropping of the rack.

In order to provide for uniform resistance to the depression of the keys, a spring 100 is connected at one end to a stud 101 on the arm 63 and at the other end to a stud 102 on the arm 44. Whenever any key is depressed, the universal bar 60 is also depressed and the rear end of the arm 63 swings upwardly thereby increasing the tension on the spring 100, except when the 9 key is depressed. The upward movement of said arm is caused by the engagement with the stepped plate 40 of the rear ends of the various keys. If the zero key is depressed, the plate 40 and arm 44 are not lifted, consequently the tension on the spring 100 increases throughout the full stroke of the zero key. If the 1 key is depressed, the tension of the spring is increased until the stroke of the key is almost completed, the balance of said stroke being accompanied by the upward movement of the plate 40 and arm 44, thereby preventing further elonga- 130

tion of said spring. As the successive keys are depressed, the spring is elongated less and less, the depression of the 9 key resulting in no elongation at all, thus equalizing 5 the weight to be lifted by the keys.

The full stroke mechanism consists of a sector shaped plate 110 pivoted about the stud 111 and having a plurality of notches 112 adapted to be engaged by the pawl 113.

- 10 The pawl is normally held in engagement with the sector by means of a spring 114 and is arranged to insure a complete movement of said plate in either direction, the pawl being reversed with respect to said 15 plate at the end of the stroke. The connection between the arm 63 and the plate 110 is provided by means of a projection 115 on the former which is received within a slot 116 on the latter.

- 20 Since the rack bar 46 descends abruptly, it tends to rebound after reaching the lower end of its stroke. In order to prevent such rebounding a stud 120 is provided on the 25 arm 44 which is adapted to be engaged by the sector plate 110, as shown in Fig. 6. During the operation of the keys, the sector plate moves upwardly in advance of the movement of said pin 120. The downward movement is insured by the spring 64 which 30 swings the universal bar upwardly, thereby moving the rear end of the bar 63 downwardly, swinging the sector 110 against the pin 120, pushing down the arm 44 and the rack bar connected thereto, and locking the 35 latter in lowermost position as shown in said figure.

- To prevent depression of the keys after the carriage has been moved laterally as far as required, that is, to the cent column, a 40 projection 121 on the carriage (Fig. 3), passes behind a lateral extension 122 on the pawl 113 thereby locking said pawl in the position shown in Fig. 7. In this position the pawl obstructs the movement of the 45 sector plate 110, thereby preventing depression of any key.

- The carriage 130, Fig. 5, is moved across the machine by mechanism shown in Fig. 2. Said carriage is secured to a bracket 131 50 and at its rear end slides on a rod 132. Said bracket is supported on an escapement plate 133 having teeth 134 on its rear side and normally drawn toward its one side by a spring 135. Step by step movement is permitted 55 by a pawl 136 which is pivoted about the pin 137 and normally held in engagement with one of the teeth 134 by a spring 138. Said escapement pawl is mounted on the rear end of a lever 139, said lever being 60 mounted on a stud 140 carried on the fixed plate 92. During the depression of any key, the eccentric stud 67 engages the forward end of said lever 139, thereby lifting it and withdrawing the pawl 136 from the teeth 65 134. A lug 141 on said lever engages the

same tooth however that has just been released, and holds the escapement mechanism against operation until said lever 139 is restored to normal position by its spring 142, at which time the pawl 136 engages 70 the next tooth, thereby permitting the escapement mechanism to move one step to the side. The carriage may be moved in the opposite direction by means of a lever 143, said pawl simply riding over said teeth 75 during such movement. Said lever 143 is pivoted about a vertical screw 144 near the rear of the machine (Fig. 1), and carries denominational keys 145. The operator depresses one of said keys and swings said 80 lever 143 to one side, to the right in the present case, causing the lower end of said key to engage a pivoted stop lever 146. This operation positions the carriage, as described more in detail in my co-pending 85 application previously referred to. The carriage has a step by step return movement as the digit keys are operated.

If it is desired to give the carriage a step by step movement across the machine without operating the keys, the following mechanism may be provided: (Figs. 10 and 11):

A plate 150 is secured at its opposite ends to the side frame of the machine. A pair of shorter plates 151-152 are arranged beneath the said plate and are supported thereby, said two plates overlapping at their ends and being supported by a pair of studs 153-154 which pass through suitable slots therein. Springs 155-156 are arranged 10 to move said plates apart, each spring being connected to a post 157 at one end secured to the stationary plate 150 and to a post 158 at the other end secured to one of the sliding plates. Said plates 151-152 are 10 provided with stems or keys 159-160 respectively, which project through openings in the side frame of the machine. Plate 152 has a rearwardly extending arm provided with a pair of cam surfaces 161-163 thereon 11 adapted to engage respectively the printing lever 77 and pin 137 about which the escapement pawl pivots. If the operator presses the key 159 inwardly, said cam surfaces move said parts 77 and 137 rearwardly, 11 thereby freeing the lever 77 from engagement with the carriage, and moving the escapement pawl 136 rearwardly thereby operating the escapement mechanism to permit the carriage to move one step laterally. 12 With this mechanism, the carriage may be repeatedly moved one step at a time. If the operator depresses the key 160, a similar cam surface 163 on the rear of the plate 151 moves the printing lever rearwardly without operating the escapement. This is done to disengage the rack 46 from the accumulator to permit taking a sub-total.

The carriage may be of any suitable construction, the one illustrated herein being 13

described more fully in the copending application referred to, and as previously stated, is arranged to move transversely across the machine, being supported on a 5 yoke 131 and the rod 132. It contains the accumulator wheels 165, 166, 167, the rack 46 meshing with the wheels 165. The wheels 166 have numeral wheels associated therewith, which are visible through an opening 10 in the top of the carriage. Said rack carries a series of fixed type 168 thereon arranged to strike against the platen 169. Suitable support for the paper 170 is also provided together with ribbon feeding 15 mechanism and other related devices. A subtraction and sub-total key 171 is also provided. The accumulator contains carrying mechanism not described herein.

As previously stated, the operator first 20 positions the carriage and then depresses the digit keys in natural order. In taking a total, the subtraction key is depressed, after which digit keys are operated corresponding to the total indicated by the 25 numeral wheels on the register. This operation turns the accumulator backward, printing the total in red and clearing the machine. A sub-total is taken in the same manner as the total, except that the operator 30 first depresses the sub-total key. The machine, however, is not cleared.

It is obvious that all of the features of improvement described herein need not be embodied in a single machine, as certain 35 features are independent of others. As previously stated, the carriage need not be operated to permit printing of the digits from left to right, but may be otherwise operated. Various other changes may be made in the 40 construction described, without departing from the spirit of the invention.

Having thus described my invention, what I claim as new and desire to secure by Letters Patent of the United States is:

45 1. In a computing machine, a combined accumulator actuating rack and type rack, a platen, key controlled means for differentially positioning said rack at the printing line and moving it against said platen, and 50 compensating means for equalizing the key resistance.

55 2. A ten key adding machine having a single combined accumulator actuating rack and type bar rack, means for holding said rack in engagement with the accumulator wheels during movement thereof in one direction, means for moving said rack out of operative relation with said accumulator and into operative relation with the platen, 60 means for holding said rack out of operative relation with either said accumulator or said platen during reverse movement, and compensating means for equalizing the key resistance.

65 3. In an adding machine, ten pivoted

keys, a universal bar moved by any key, a printing cam, means connecting said bar and said cam and providing a loose connection there between, a spring tending to move said cam with said means, and a lock to 70 prevent such movement, said lock being released toward the end of the movement of said bar.

4. An adding machine having ten pivoted keys, a universal bar moved by any 75 key, an arm moving with said bar, a printing cam, a spring engaging said bar and said cam and tending to move the latter with the former, and a lock to prevent such movement, said lock being released by said arm toward the end of its movement whereby said spring may move said cam.

5. In a ten key adding machine, a pivotal support, keys pivoted thereon, a universal 85 bar pivoted to said support, an arm turning with said bar, a printing cam pivoted on said support, said cam having slots therein, studs on said arm received within said slots to guide said cam, a spring coiled about said pivotal support and engaging 90 said arm and said cam to move the latter with the former, a lock preventing such movement, said arm being arranged toward the conclusion of its movement to disengage said lock, whereby said spring abruptly 95 moves said cam, and a type bar whose printing movement is controlled by said cam movement.

6. In a ten key adding machine, a pivotal support, keys pivoted thereon, a universal 100 bar pivoted to said support, an arm turning with said bar, a printing cam pivoted on said support, said cam having slots therein, studs on said arm received within said slots to guide said cam, a spring for moving the 105 cam with the arm, a lock preventing such movement, said arm being arranged toward the conclusion of its movement to disengage said lock, whereby said spring abruptly moves said cam, and a type bar whose printing movement is controlled by said cam movement.

7. An adding machine comprising a plurality of pivoted key levers, a series of stops, a member arranged to be engaged by any 115 of said key levers and moved differentially until limited by said stops, a yielding connection between said key levers and said member to permit movement of said key levers after said member has stopped its 120 movement, and printing mechanism whose operation is controlled by said subsequent movement.

8. In an adding machine, a series of ten pivoted digit keys, each having a pair of 125 lugs at its rear end, a spring supported by said lugs, a pivoted frame carrying a plate having a series of steps on opposite sides thereof, a series of pivoted stops, the springs on said keys being arranged to engage one 130

- series of steps to swing said plate and said frame, and said stops being arranged to be engaged by said other series of steps to limit said swinging movement, said springs permitting further movement of said keys after the movement of said plate has been arrested, and printing mechanism controlled by said further movement, said stops being engaged by one of said pair of lugs on each key during the return movement thereof for moving them out of the path of travel of said plate.
9. In an adding machine, a series of ten keys each having a yielding member thereon, a pivoted stepped plate engaged by said members, a printing rack movable with said plate, stops to limit such movement, said yielding members permitting movement of said keys after the movement of said plate has been arrested, and means operated by such further movement to move said rack at right angles to its first mentioned movement.
10. In an adding machine, a series of ten pivoted digit keys, a pivoted frame carrying a plate having a series of steps on opposite sides thereof, a series of pivoted stops, said keys being arranged to engage one series of stops to swing said plate and said frame, said stops being arranged to be engaged by said other series of steps to limit said swinging movement, and being engaged by said keys during the return movement thereof for moving them out of the path of travel of said plate, and a register controlled by the movement of said frame.
11. In a computing machine, the combination with a plurality of keys, of a single type rack, intermediate mechanism whereby said type rack may be positioned differentially by any of said keys, a carriage, a lever for positioning said carriage prior to the depression of said keys, an escapement controlled by said keys for moving said carriage step by step to its initial position, and means preventing depression of said keys after said initial position has been reached.
12. A ten key adding machine comprising a body, a carriage laterally movable with respect thereto, digit keys, a single vertically reciprocable rack, mechanism whereby said rack may be differentially positioned by any of said keys, compensating means for equalizing the key resistance, an accumulator in said carriage and a platen to the rear of said accumulator, said rack projecting upwardly between said accumulator and platen and having teeth on the front side to coöperate with said accumulator and fixed type on the rear side to strike against said platen, the co-operation thereof with said accumulator or said platen being accomplished by a forward or backward movement of said rack, effected also by the movement of said keys.
13. In a computing machine, a plurality of digit keys, a printing rack differentially positioned thereby, a full stroke mechanism, and means coöperating with the same and with said rack for locking all of said keys against actuation.
14. In an adding machine, a plurality of pivoted key levers, a universal bar moved thereby, a pivoted section movable with said universal bar, a pivoted frame moved differentially by said key levers, a rack movable with said frame, a register operated by said rack and means on said frame engaged by said sector for restoring the latter to its initial position and locking it against rebound.
15. In a ten key adding machine, a series of keys, a frame movable with any of said keys, a spring secured to said frame and to a movable support to resist movement of said keys, the latter imparting a variable movement to said support to permit said spring to yield an inverse variable amount to uniformly tension said keys and a register operated by said keys.
16. In a computing machine, a series of ten keys, a stepped plate arranged to be differentially positioned thereby, a universal bar movable with said keys, a member movable with said stepped plate, a spring having one end movable with said universal bar and the other end movable with said member whereby said spring coöperates with said stepped plate and associated parts to insure uniform resistance to the operation of said keys and a register operated by said plate.
17. A computing machine comprising a combined accumulator actuating rack and type rack, a platen, key controlled means for differentially positioning said rack at the printing line and moving it against said platen, and a cam which coöperates with said rack upon restoration of the latter to initial position, to prevent rebounding thereof.
18. In a ten key adding machine, pivoted digit keys, a combined accumulator actuating rack and type rack differentially positioned thereby, compensating means for equalizing the key resistance, an accumulator, a platen with which said rack coöperates, means for moving said rack from engagement with said accumulator into engagement with said platen, and a timing mechanism insuring the cessation of the positioning movement of said rack prior to its movement against said platen.
19. In a computing machine, a series of ten pivoted digit keys, a pivotally mounted universal bar arranged to be moved by the depression of any of said keys, a printing cam and means associated with said universal bar for moving said cam, a stepped member arranged to be moved differentially by said keys, means for positively limiting the movement of said member, a single combined accumulator and type rack moving

with said member, positive stops for limiting the movement of said member, an accumulator and a platen with which said rack coöperates, connections between said member 5 and keys permitting an additional movement of the latter and of said printing cam after said rack has operated said accumulator, and means controlled by such additional movement of said printing cam for moving 10 said rack into engagement with said platen.

20. In a computing machine, a series of ten pivoted digit keys, a pivotally mounted universal bar arranged to be moved by the depression of any of said keys, a printing 15 cam, means associated with said universal bar for moving said cam, a stepped member arranged to be moved differentially by said keys, means for positively limiting the movement of said member, a single combined 20 accumulator and type rack moving with said member, positive stops for limiting the movement of said member, an accumulator and a platen with which said rack coöperates, a carriage in which said accumulator 25 and platen are mounted, an escapement mechanism for said carriage, means associated with said universal bar for operating said escapement mechanism, connections between said stepped member and keys permitting 30 an additional movement of the latter and of said printing cam after said rack has operated said accumulator, and means controlled by such additional movement of said printing cam for moving said rack into engagement with said platen. 35

21. In a ten key adding machine, a series of digit keys, a register mounted in a carriage and actuated by said keys, an escapement mechanism for said carriage actuated 40 by the depression of any key, a universal bar also actuated by movement of any key, means comprising a sector and pawl for insuring a full stroke of said bar, and means on said escapement mechanism arranged to engage said pawl to lock the latter and hence 45 said universal bar and keys when said carriage has reached the limit of its travel.

22. In a ten key adding machine, a plurality of pivoted key levers, a register mounted 50 in a carriage and actuated by said keys, a universal bar moved by said keys, a pivoted sector movable with said universal bar, a pivoted frame moved differentially by said keys, means on said frame engaged by said 55 sector for restoring the latter to its initial position and locking it against rebound, an escapement mechanism for said carriage, means operated by said universal bar for tripping said escapement mechanism when 60 any key is depressed, a pawl arranged to engage said sector to permit movement thereof first in one direction and then in the other, and means associated with said escapement mechanism for locking said pawl in position 65 to prevent movement of said sector and

hence actuation of said keys after said escapement mechanism has reached the limit of its travel.

23. In a computing machine, a differentially movable rack, a printing lever having 70 sliding engagement with said rack, a stationary support, a spring latch on said lever arranged to engage said support while said rack is descending, and a projection on said rack for disengaging said latch from said 75 support when said rack reaches lowermost position.

24. In a ten key adding machine, a series of keys, a rack differentially positioned thereby, a printing lever guiding said rack, 80 a universal bar moved by said keys, a full stroke mechanism for said bar, said mechanism serving also to lock said rack in lowermost position, and a latch on said printing lever for controlling said rack during its 85 downward movement, said latch being rendered inoperative by said rack when the latter reaches lowermost position.

25. In a ten key adding machine, a pivoted frame, a stepped plate thereon, a rack 90 pivotally mounted on said frame, digit keys for moving said plate and said frame, a universal bar moved by said keys, a spring co-operating with said bar and with said frame for balancing said rack and insuring uniform 95 resistance to the depression of said keys and a register actuated by said rack.

26. In a ten key adding machine, a pivoted frame, a stepped plate thereon, a rack pivotally mounted on said frame, digit keys 100 for moving said plate and said frame, a universal bar moved by said keys, a spring co-operating with said bar and with said frame for balancing said rack and insuring uniform 105 resistance to the depression of said keys, means associated with said universal bar for locking said rack in lowermost position, and a register actuated by said rack.

27. In an adding machine, a single reciprocable rack bar, a printing lever with which 110 said rack bar has sliding engagement, and by which its movement is directed, a cam for moving said lever, a lock preventing movement of said cam, keys, a second cam to render said lock inoperative, and a member 115 moved by any key to operate said cam, said member having adjustable means to control the timing of the unlocking operation.

28. In a computing machine, a register, a rack therefor, a rack frame, a universal bar, 120 a frame therefor associated with said rack frame, keys arranged to operate said rack differentially and said universal bar a uniform amount, a spring co-operating with said rack frame, and a cam also co-operating with 125 said frames, the weight of said rack and its frame aiding in restoring said universal bar and keys to initial position, and said cam serving to maintain said rack and its frame in initial position. 130

29. In a computing machine, a combined accumulator actuating rack and type rack, a platen, and key controlled means for differentially positioning said rack at the printing line and moving it against said platen, said means including two relatively movable spring-connected members serving to partially balance the weight of the rack against the weight of the keys to lighten the key stroke, and a full stroke mechanism for 15 said keys.
30. In a computing machine, a combined accumulator actuating rack and type rack,

a platen, and key controlled means for differentially positioning said rack at the printing line and moving it against said platen, said means including two relatively movable spring-connected members serving to partially balance the weight of the rack against the weight of the keys to lighten the key stroke, and a full stroke mechanism for 20 said keys.

In witness whereof, I hereunto subscribe my name this 27th day of May A. D., 1916.

OLIVER D. JOHANTGEN.
